Application March 10, 1948, Serial No. 13,989

17 Claims. (Cl. 78—13)

1

The present invention relates to improvements in hammer frames for steam drop hammers, or the like, and more specifically concerns frames of this type which are fabricated by welding together steel parts instead of and as an improvement over the conventional casting of hammer frames.

An important object of the present invention is to provide in a fabricated steam drop hammer frame an improved hammer guide supporting structure.

Another object of the invention is to provide a fabricated steam drop hammer frame made from steel plate and an improved mounting in permanent association therewith of a hammer track guide supporting structure.

A further object of the invention is to provide in a steam hammer frame construction an improved hammer track arrangement.

Still another object of the invention is to provide in a steam hammer track structure improved means for effecting adjustments of the track.

Other objects, features and advantages of the present invention will be readily apparent from the following detailed description of certain preferred embodiments thereof taken in conjunction with the accompanying drawings, in which:

Figure 1 is a front elevational view of a pair of steam drop hammer frames showing the same in operative relationship and with environmental details of a complete drop hammer assembly shown more or less schematically.

Figure 2 is an enlarged front elevational view of one of the hammer frames, in this instance the left hand hammer frame as it appears prior to assembly in the drop hammer organization.

Figure 3 is an inside elevational view of the hammer frame shown in Fig. 2.

Figure 4 is a vertical sectional view taken substantially on line IV—IV of Fig. 3.

Figure 5 is a vertical detail sectional view on an enlarged scale taken substantially on the line V—V of Fig. 2.

Figure 6 is a horizontal sectional view taken substantially on the line VI—VI of Fig. 5.

Figure 7 is a fragmentary inside elevational view of a modified form of hammer frame.

Figure 8 is a vertical sectional detail view taken substantially on the line VIII—VIII of Fig. 7.

Figure 9 is a horizontal sectional detail view taken substantially on the line IX—IX of Fig. 8.

The hammer organization in which the present invention is adapted to be used may, as shown in Fig. 1, comprise a supporting base 15 upon which are mounted left and right frames 16 and 17 secured to the base as by means of bolts 18.

2

Upon the frames is a tie plate 19 upon which is supported a steam cylinder casting 20, this casting and the tie plate 19 being secured to the tops of the frames as by means of bolts 21.

Each of the frames 16 and 17 carries a conventional hammer guide 22 for vertically reciprocably guiding a drop hammer 23 carrying a die 24 cooperable with a stationary or lower die 25 mounted upon the base 15 through the medium of a die anvil or base member 27. The hammer 23 is reciprocated by means of a piston rod 28 having at its upper end a piston 29 driven reciprocably in the cylinder 20 by steam under the control of standard control means 30 appropriately mounted on the frame 17.

According to the present invention each of the frames 16 and 17 is fabricated from steel plate which may be cold-rolled steel, each of the frames being of substantially the same construction and the description of the details of the structure of one therefore sufficing for an understanding of the details of structure of the other. Therefore, while Figs. 2—6, inclusive, show various details of structure of the left hand side frame 16 of the assembly, it will be understood that the details of the right side frame 17 correspond substantially identically.

The body of the side frame is constructed of substantially tubular, box-like vertically elongated form and comprises an outer side frame plate 31, a front plate 32, a rear plate 33, an upper inner side plate 34 and a lower inner side plate 35. The outer side plate 31 preferably extends diagonally downwardly and outwardly to a lower vertical portion 37 which is disposed parallel to the lower inner side plate 35 which extends in a vertical plane. The upper inner side plate 34 also extends in a vertical plane. The front and rear plates 32 and 33 preferably extend in generally vertical planes spaced apart. All of the plates are secured together in an integral, rigid welded structure of generally box-like or angular tubular cross section.

The outer side plate 31 is preferably of a relatively heavy gauge steel plate, as is also the lower inner side plate 35, while the front and rear plates 32 and 33 and the upper inner side plate 34 may be of lighter gauge structure.

The lower portion 37 of the outer side plate and the lower inner side plate 35 are preferably formed to flare downwardly edgewise and, together with the lower edges of the front and rear plates 32 and 33 are welded fixedly to a relatively heavy bottom plate 38 which is recessed on the bottom as indicated at 39 for efficient seating and attachment to the complementary shaped base

15. Bolt holes 40 formed through the base plate 38 outwardly of the front and rear plates 32 and 33, respectively, afford passage for the shanks of the attachment bolts 18.

At its upper end, the side frame assembly includes a top plate 41 which is welded to the upper edges of the outer side plate 31, the front and rear plates 32 and 33, and the inner upper side plate 34. Bolt holes 42 in the upper plate 41 are receptive of the upper attachment bolts 21.

Each of the side frames 16 and 17 is equipped with a hammer guide supporting structure 43 formed of relatively heavy, welded steel plate construction. To this end, each of the hammer guide supporting structures 43 comprises relatively heavy vertical front and rear plates 44 and 45 respectively, a fairly heavy vertical back plate 47 having the vertical edges thereof intermediate the back margins of the side plates and permanently and thoroughly welded thereto, and top and bottom plates 48 and 49 respectively welded between the respective upper and lower margins of the front and rear plates and to the upper and lower edges of the back plate 47.

The rigid hammer guide supporting structure 43 thus constructed is assembled with the body of the side frame set into the inner side of the frame, the front and rear plates 32 and 33 being formed with appropriate angular cut outs 50, for receiving and supporting the supporting assembly, the front and rear plates 32 and 33 thus directly supporting the front and rear plates 44 and 45 of the supporting structure. The lower edge of the inner upper side plate 34 engages the upper plate 48 and the upper edge of the lower inner side plate 35 engages under the bottom plate 49. The assembly thus effected is permanently and fixedly welded into a unitary structure.

Additional reinforcement of the assembly is effected by the provision of triangular gusset or reinforcing plates 51 disposed in vertically spaced series in spaced horizontal planes at the inner re-entrant corners formed by the back of the guide supporting frame 43 and the front and rear plates 32 and 33 respectively (Figs. 4 and 6).

For supporting one of the hammer guides 22 therein, the guide supporting structure 43 is formed with finished parallel offset vertical supporting and guide surfaces 52 on the front and rear plates 44 and 45 and a lower offset finished supporting surface 53 on the bottom plate 49. Thus the hammer guide 22 is slidably adjustable by means of a conventional guide-adjusting wedge 54 (Fig. 1). This wedge is slidably adjustable between the hammer guide and the finished vertical offset pad or surface 55 on the inner side of the back plate 47. Adjustment of the wedge 54 is adapted to be effected by a conventional wedge adjusting nut 57 which is received in a pocket 58 (Figs. 3 and 4) acting on a customary wedge rod projecting up through a slot 59 in a pocket forming plate 60 spaced below the top plate 48 and welded permanently in place in the recess provided by the front and rear plates 45 and the back plate 47, with tapered front and rear spacer blocks 61 and 62 defining the front and rear of the pocket 58. The plate 58 and the blocks 61 and 62 are, of course, all welded in permanent unitary assembly in the guide supporting structure. Clearance for the upper end of the wedge adjusting rod is provided by a slot 63 in the top plate 48. The usual locking pin for the wedge adjusting nut 62 is accommodated in a bore 64 coaxial through the rear plate 45

and the block 62. It will be observed that the pocket forming plate 58 has the lower surface thereof formed with an offset finished hammer guide receiving surface 65.

5 The back plate 47 has bores 67 at appropriate vertically spaced intervals aligned with bores 68 formed in the outer side plate 31 of the frame for accommodating hammer guide securing bolts 69, appropriate bosses 70 being welded to the 10 outer face of the side plate 31 about the apertures 68 and having vertical faces for receiving the thrust of the securing nuts of the bolts 69.

The welded construction thus described for the 15 hammer frames is especially valuable and particularly advantageous over a cast structure since the steel plates of which the frames are constructed are capable of withstanding the terrific stresses and strains incident to operation of the drop hammer 23 and the great vibrations incident to such operation much better than the 20 conventional cast frames. The steel plates will not crack, chip or break, they do not have blow holes such as castings or shrinkage stress areas or flaws. If any section, large or small of the 25 assembly should become distorted or damaged in any way it can be repaired by welding, and generally without removal from the hammer organization.

It will be noted that the guide-supporting 30 structures or sub-frames are of a relatively massive construction and are thus adapted to absorb and withstand the relatively great shocks attendant upon hammer impact which is obviously to a very substantial extent concentrated at the 35 hammer guides in addition to the dies which absorb the working impact of the hammer. Vertically directed stresses are efficiently transmitted to the supporting plates for the guide-supporting structure or sub-frames in the planes 40 of the supporting plates which, of course, is their greatest strength. Furthermore outward force on the hammer guide supporting sub-frames is efficiently resisted by the main frame plates through the unitary welded assembly and 45 by reason of the transmission of the principal force in the planes of the front and rear plates 32 and 33 into which the sub-frames are respectively set. In addition to the strength inherent in the welded assembly of the back plate 50 47 of the guide-supporting structure and the supporting plates of the guide-supporting structure, the reinforcing angle plates 51 will transmit any unusual thrusts against the back plate with which associated to the front and rear 55 plates 32 and 33 of the main frame.

In the modification disclosed in Figs. 7, 8 and 9, the general structure of the side frame remains substantially the same as described in connection with the side frames 16 and 17, but provision is 60 made for a unique adjustable hammer guide arrangement which entirely eliminates the conventional vertically adjustable wedge bar or shims and attains a number of important advantages over prior constructions. The body of 65 the modified frame comprises an outer side wall 70, similar front and rear walls 71 and 72, respectively, an upper inner wall plate section 73 and a lower inner wall plate section 74, all of the wall panels being secured in unitary, permanent 70 substantially rigid welded assembly forming a generally box-like or tubular cross section, similarly as in the case of the frames 16 and 17 already described.

In the modification, the hammer guide supporting structure is also substantially the same

as in the previously described forms of side frames for the drop hammer assembly, comprising relatively massive side plates 75 and 77 which are set into respective angular cut outs 78 therefor in the front and rear plates 71 and 72. The back plate 79 is disposed edgewise between the margins of the side plates 75 and 77 and is short enough to engage at its upper and lower ends with upper and lower plates 80 and 81, respectively, which as best seen in Fig. 7 extend edgewise between the upper and lower margins of the side plates 75 and 77. Thrust reinforcement for the back plate 79 and the adjacent back edges of the side plates 75 and 77 is afforded by horizontal generally rectangular bracket or gusset plates 82 disposed at the re-entrant corners afforded by the inner surfaces of the front and rear wall plates 71 and 72 and the back of the hammer guide supporting unit. All of the several parts of the hammer guide-supporting unit are, of course, welded into a unitary assembly and welded into unitary assembly with the body of the frame.

A novel form of hammer track or guide 83 is accommodated by the modified guide-supporting structure for adjustment in a novel manner by retraction or protraction relative to the guide-supporting structure. To this end, the hammer guide 83 has a more or less conventional grooved hammer track or guide face 84 and parallel substantially finished bearing side faces 85 which engage with raised or offset parallel bearing pads 86 formed on the opposing inner faces of the side walls 75 and 77 of the track-supporting structure. In this way the track member 83 can be slidably protracted or retracted for adjustment between the side plate members 75 and 77.

Instead of the customary wedge bar for effecting such adjustment of the hammer track or guide 83, the present invention provides upper and lower retaining and adjustment bolts 87 and 87' respectively. Each of these bolts has an enlarged body portion having an inner reduced end portion 88 extending through a suitable bore 89 in the guide member 83 and threadedly engaged with a retaining nut 90 received within a recess 91 by which the nut and the tip of the bolt are set far enough into the guide member 83 to clear the hammer guide track face 84. The shoulder provided by the enlarged body portion of the bolts 87 and 87' at the base of the reduced diameter inner end portion 88 provides a thrust shoulder for the back of the guide member 83 and may, if desired, be set into a counterbore 92 about the back end of the bolt passage bore 89.

Respective clearance apertures 93 are provided in the back plate 79 for the bolts 87 and 87'.

At their respective outer end portions, the bolts 87 and 87' are provided with means for effecting and retaining adjusted conditions of the bolts. To this end each of the bolts may be formed with a reduced diameter threaded portion 94 extending through a thrust bracket 95. Each of the brackets 95 is preferably formed as a relatively heavy gauge, generally U-shaped member having oppositely extending lateral flanges 97 at the extremities of the leg portions thereof, and disposed with the leg portions in vertical planes projecting through respective apertures 98 provided therefor in the back plate 79 and having the flanges 97 engaging the inner face of the back plate in thrust relation at the opposite sides of the aperture 98. To facilitate assembly, the aperture 98, in each instance, is preferably long enough in a vertical direction to permit assembly

therethrough of the thrust bracket 95 when turned 90° around with the flanges 97 extending up and down and the bracket, after reception entirely within the tubular chamber provided interiorly of the frame structure, being then turned to proper assembly position and projected through the aperture 98 until the flanges 97 engage the side wall plate 70. The bracket 95 is then welded in place permanently. A compression block or panel 99 is preferably welded between the heels of the flanges 97 to avoid displacement of the flanges toward one another under extreme thrust load imparted to the bracket 95 by the associated adjustment and thrust pin or bolt 87 or 87', as the case may be. An aperture 100 through the compression block 99 is coaxially aligned with an aperture 101 in the web of the thrust bracket 95 to clear the threaded outer end portion 94 of the bolt freely therethrough.

Adjustment and retention of each of the bolts 87 and 87' with respect to the bracket 95 is effected by means of a thrust nut 102 and a lock nut 103 threaded on the outer threaded end portion 94 within the thrust bracket 95, and a retaining nut 106 threaded on that part of the threaded portion 94 which projects out through the bracket aperture 101. Thus, to effect proper hammer guiding adjustment of the guide member or track 83, the bolt nuts 102, 103 and 106 are appropriately manipulated for each of the bolts 87 and 87' to attain the precise adjustment desired with respect to the hammer to be guided. A particular advantage of this form of adjustment resides in the fact that all need for shims between the guide track member and a wedge bar for wear adjustment or the like is entirely eliminated and relatively acute adjustment in this respect is attainable through the medium of the adjustment and retaining thrust bolts 87 and 87'.

Back and forth or sidewise movement of the track or guide member 83 is substantially eliminated by relatively close sliding fit between the side faces 85 and the bearing pads 86 of the side plates of the guide-supporting structure. The up and down movements of the guide member 83 resulting from reciprocations of the hammer usually present a more serious problem, but are effectively prevented in the present construction by the provision of respective upper and lower locking wedges 104 which are interposed between the respective upper and lower ends of the guide member 83 and the upper and lower plates 80 and 81 of the guide supporting structure. For this purpose each of the wedge blocks 104 has a horizontal flat surface 105 which engages with a horizontal offset bearing pad 107 on the opposing face of the respective upper and lower plates 80 and 81. For engaging the guide member 83 wedgingly, each of the wedge blocks 104 is formed with an oblique bearing face 108 opposing the respective end of the guide member which for this purpose is formed with a complementary oblique bearing end face 109 at each end.

A wedge rod or bolt 110 extends from the back of each of the wedge blocks 104 through an appropriate aperture 111 in the back plate 79 and on through the interior of the frame assembly with the outer end portion of the bolt extending through an aperture 112 in the outer side wall plate 70 and with such end portion threaded as indicated at 113 to receive a tightening nut 114 which bears against a thrust boss 115 for the uppermost of the bolts and a thrust boss 117 for the lower of the bolts welded about the respective bolt aperture 112 at the outer face of the side

wall plate 70. Thus, adjustment of the guide member 83 is first effected by appropriate manipulation of the adjustment and retaining bolts 87 and 87' while the wedge blocks 104 are loose. Then, the wedge blocks 104 are drawn tight between the ends of the guide member 83 and the respective upper and lower guide-supporting frame plates 80 and 81, by tightening the nuts 114. This effectively locks the guide member 83 against vertical movement in either direction. This also saves the bolts 87 and 87' from strains to which they might be subjected in the operation of the hammer by possible movements of the guide member 83 in a vertical direction. This arrangement also saves the bolts 87 and 87' from any tug stresses since by the action of the wedge blocks 104 the bolts 87 and 87' are placed under longitudinal compression which is effectively resisted by the thrust brackets 95. Hence the bolts 87 and 87' are saved from the usual shear and tug stresses that in conventional arrangements have caused fracture and breakage of the guide bolts. Furthermore should for any remote reason either of the bolts 87 or 87' break, it cannot come through the guide member 83 and thus create a dangerous condition in the operation of the hammer 23.

Another very important advantage of the mounting and adjustment of the guide track member 83 resides in the fact that it can be retracted far enough to clear the hammer or ram 23 entirely to facilitate placement and removal of the latter. For this purpose the thickness of the guide member 83 is so proportioned relative to the depth of the pocket or housing provided by the supporting structure that there is enough space between the back face of the guide member and the back plate 79 to accommodate ram-clearing retraction of the guide member. As a result, in order to remove the ram all that need be done is to disconnect the piston rod therefrom, push it out of the ram, loosen and retract the guides 83, and the ram is then clear for removal. Replacement involves merely the reversal of these steps. With the conventional wedge bar type of adjustment for the guide track members it was necessary to remove the steam gland head, remove the piston rod out through the cylinder and raise the ram above the guides for removal. Furthermore, where it was necessary to shim or line the adjustment wedge behind the guides to take care of wear, it was necessary to remove the ram entirely to gain access behind the guides. By the present invention any such adjustment is effected quickly and easily from the sides of the frame and without disturbing the ram.

Permissible symbolism indicative of welding has been deliberately omitted from the present drawings, since welding is a well understood expedient, and its effects in affording a homogeneous, solid well knit unitary assembly of the welded members. By the present invention an important and valuable relationship of various elements in hammer frames has been attained whereby the welded construction of such hammer frames is made practical and thus eliminates the heavy, overly massive and yet relatively unreliable castings that have heretofore been deemed essential. In addition, of course, other valuable improvements have been taught by the present disclosure as is evident from the foregoing description.

The present application is a continuation-in-part of my copending application Serial No.

522,927, filed February 18, 1944, and now abandoned.

It will, of course, be understood that various details of construction may be varied through a wide range without departing from the principles of this invention and it is, therefore, not the purpose to limit the patent granted hereon otherwise than necessitated by the scope of the appended claims.

10 I claim as my invention:

1. In combination in a hammer frame construction, a unitary assembly of individual steel plates comprising spaced coextensive side plates, an outer plate, and longitudinally separated upper and lower inner plates, all welded together into a solid unitary member of tubular cross section, and a hammer guide supporting structure comprising an elongated box-like assembly of individual steel plates of heavier gauge than said side and inner plates and welded into a unitary structure, said guide supporting structure being set into and supported by the inner edges of the side plates between said inner plates and being welded into unitary assembly with such plates.

2. In a drop hammer frame construction a unitary assembly of steel plates comprising spaced apart coextensive side plates, a substantially coextensive outer plate, and relatively short upper and lower inner plates, the plates being welded together into a unit of box-like cross section, and a hammer guide supporting structure set into the inner edges of the side plates between said inner plates and intimately welded to the side and inner plates, said guide-supporting structure including a relatively massive head structure having wedge rod and adjusting nut recesses.

3. In a drop hammer frame unit, a welded tubular assembly of generally upright plates providing a tubular column of generally angular cross section, an opening in one face of said column comprising angular cut outs in the two plates forming opposite sides of the column, and a relatively massive box-like guide supporting frame comprising side plates, a back plate and top and bottom plates of heavier gauge than said side plates and welded together into an angular unitary assembly, said guide-supporting frame being set into said opening and permanently welded therein to form with the column a unitary structure.

4. In a drop hammer frame construction, a columnar assembly of vertical plates including an outer plate, side plates and upper and lower inner plate sections, a top plate and a bottom plate, all of the plates being welded together into a unitary assembly of angular tubular cross section and with the adjacent edges of the upper and lower inner plates spaced apart, and a separately formed guide-supporting frame having walls substantially thicker than said side and inner plates received between said spaced edges and welded permanently to the side plates and to said upper and lower inner plate sections.

5. In a drop hammer frame construction, a columnar assembly of vertical plates including an outer plate, side plates and upper and lower inner plate sections, a top plate and a bottom plate, all of the plates being welded together into a unitary assembly of angular tubular cross section and with the adjacent edges of the upper and lower inner plates spaced apart, a separately formed guide-supporting frame received between said spaced edges and welded permanently to the side plates and to said upper and lower inner

plate sections, and reinforcing gusset plates welded to the guide-supporting frame and the side plates at the inside of the hammer frame column.

6. In combination in a drop hammer frame construction, vertical back and side plates and upper and lower inner plate sections, said plates being welded together into a column of angular cross section and tapering from the top to the bottom of the column, a bottom plate to which lower back and side plates and the lower inner plate section are welded, a top plate to which the upper edges of the back and side plates and the upper edge of the upper inner plate section are welded, a hammer guide-supporting frame set into the column between the opposing edges of said inner plate sections and welded permanently in place in the column, said bottom plate being substantially wider than the spacing between the bottom edges of the side plates and said lower inner plate section being of downwardly flaring outline and thus affording a strong support for the bottom of the hammer frame guide-supporting structure.

7. In combination in a columnar drop hammer frame structure, back side and inner plates assembled into an angular column and having their upper edges in generally the same plane, a top plate disposed in a horizontal plane and welded to the upper edges of the first mentioned plates, said top plate extending laterally beyond the sides of the side plates and having bolt holes therethrough for attachment of a head structure for a drop hammer frame on top of the column.

8. In combination in a hammer frame construction of the character described, means defining a columnar frame body, said frame body having a recess therein opening from the inner side thereof, and a hammer frame guide mounted therein, said hammer frame guide comprising relatively heavy gauge spaced steel side plates, a back plate disposed edgewise between the inner margins of the side plates, a bottom plate disposed between the bottom margins of the side plates and below the bottom edge of the back plate, and a top plate disposed between the upper margins of the side plates and on the upper edge of the back plate, all of said plates being permanently welded together into a unitary assembly and the assembly being welded into unitary assembly within said opening in said frame body.

9. In combination in a hammer frame construction of the character described, means defining a columnar frame body, said frame body having a recess therein opening from the inner side thereof, and a hammer frame guide mounted therein, said hammer frame guide comprising relatively heavy gauge spaced steel side plates, a back plate disposed edgewise between the inner margins of the side plates, a bottom plate disposed between the bottom margins of the side plates and below the bottom edge of the back plate, a top plate disposed between the upper margins of the side plates and on the upper edge of the back plate, all of said plates being permanently welded together into a unitary assembly and the assembly being welded into unitary assembly within said opening in said frame body, and reinforcing angle plates welded in thrust relationship to said back plate and the inner faces of the side walls of the frame body.

10. In combination in a hammer frame construction of the character described, a columnar

tubular frame body having a recess opening to the inner side thereof, and a box-like hammer guide supporting structure mounted in said recess and fixedly secured therein, the guide structure including spaced vertical walls and top and bottom walls, all of said walls having offset accurately machined bearing surface pads and said top and bottom walls having opposing offset bearing pad surfaces, a back plate also having an offset bearing pad surface, the areas of all of said walls of said back plate adjacent the junctures of the respective walls and said back plate being inset whereby to facilitate welding of said walls and back plate into a unitary assembly without affecting said bearing pad surfaces.

11. In combination in a hammer frame construction, a frame body having an inner side and an opposite outer side, a hammer guide-supporting structure providing an angular pocket opening to the inner side of the frame and closed from the outer side of the frame body by a back on said structure, a hammer guide member slidably retractably mounted in said pocket, and means comprising members extending from said guide member through the back of the guide-supporting structure and accessible from the outer side of the frame for retractional and protractional adjustment of the guide member, said adjustment means comprising adjustment bolts secured to the guide member and having thrust shoulder engagement with the back of the guide member.

12. In combination in a drop hammer guide frame, a frame body having inner and outer sides, a hammer guide-supporting structure on said inner side of the frame body and having a guide pocket defined by a back, a hammer guide member mounted in said pocket, thrust bolts extending from said guide member through said back of the supporting structure, and thrust brackets at the outer side of the frame to which said bolts are attached in outwardly thrusting relation to resist hammer imposed outward thrust on the hammer guide member.

13. In combination in a drop hammer guide frame, a frame body including an outer wall and an inner side, said outer wall having an inner side facing toward the inner side of the frame, a hammer guide-supporting structure at the inner side of the frame having a guide pocket and having a back facing toward said inner side of said outer wall, a hammer guide member mounted in said pocket, thrust bolts extending from said guide member through said back of the supporting structure, and thrust brackets at the outer wall of the frame to which brackets said bolts are attached, said brackets being of generally U-shape and having thrust flanges engaging at the inner side of the outer wall of the frame.

14. In combination in a drop hammer guide frame, a frame body including an outer wall and an inner side, said outer wall having an inner side facing toward the opposing surface of the inner side of the frame, a hammer guide-supporting structure at the inner side of the frame having a guide pocket and having a back opposing the inner side of said outer wall, a hammer guide member mounted in said pocket, thrust bolts extending from said guide member through said back of the supporting structure, thrust brackets at the outer wall of the frame having respective body portions to which said bolts are attached, said body portions of the brackets being of generally U-shape and having thrust

flanges engaging at the inner side of the outer wall of the frame, said flanges having heel portions at juncture with the bracket body portions, and compression blocks secured between the heel portions of said flanges.

15. In combination in a hammer frame construction, a frame body having inner and outer sides, a hammer guide supporting structure at the inner side of the frame and providing a guide pocket, a hammer guide adjustably mounted in said pocket, thrust bolts extending from said guide member to the outer side of the frame, a thrust bracket for each of said bolts on the outer side of the frame and having a bolt-engaged apertured portion spaced rearwardly from the frame, the outer end portion of each of the bolts being threaded and extending through the apertured portion of its bracket, and adjustment and retaining and lock nuts on said threaded portion cooperating in thrust relation with the respective opposite sides of the bracket portion.

16. In combination in a hammer frame construction of the character described, a frame member having an outer side wall and an inner side structure including a guide pocket, a guide member slidably inwardly and outwardly in said pocket, a bolt carried by said guide member in inward and outward thrust relationship and extending outwardly through said frame structure, said outer side wall having an aperture therein, the outer end portion of said bolt projecting through said aperture, and a thrust bracket secured in said aperture and projecting outwardly therebeyond and having a thrust portion connected to the outer end portion of said bolt through the medium of attachment nuts carried threadedly by said outer end portion of the bolt, said bracket affording an access opening between said thrust portion and said outer side wall.

17. In combination in a hammer frame construction of the character described, a pair of spaced vertically extending front and rear plates, an outer side plate, an inner side structure including a hammer guide frame and a vertical plate below said hammer guide frame, a top plate secured on top of said outer side and front and back plates, and a bottom plate secured to the lower edges of said front and back plates and said outer side plate and said lower inner side plate, said front and rear plates being inset relative to the upper and lower edges of the rear plate and the upper and lower plates extending forwardly and rearwardly beyond the front and rear plates and having bolt holes therethrough for reception of bolts to attach the frame construction to top and base members of a drop hammer installation.

ROY A. KROPP.
